(57) **CLAIM**

The ornamental design for panel for air-conditioner, as shown and described.

DESCRIPTION

FIG. 1 is a perspective view of a panel for air-conditioner showing my new design;

FIG. 2 is a front view thereof;

FIG. 3 is a rear view thereof;

FIG. 4 is a plan view thereof;

FIG. 5 is a bottom view thereof;

FIG. 6 is a left side view thereof;

FIG. 7 is a right side view thereof;

FIG. 8 is a cross-sectional view thereof along the line 8-8 in FIG. 2; and,

FIG. 9 is a perspective view thereof of used state.

The broken lines depict portions of the panel for air-conditioner that form no part of claimed design.
